UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

NEEDLE-THREAD-CONTROLLING MECHANISM FOR SEWING-MACHINES.

1,366,364.

Specification of Letters Patent.

Patented Jan. 25, 1921.

Application filed May 11, 1918. Serial No. 234,009.

To all whom it may concern:

Be it known that I, ALBERT H. DE VOE, a citizen of the United States, residing at Westfield, in the county of Union and State 5 of New Jersey, have invented certain new and useful Improvements in Needle-Thread-Controlling Mechanisms for Sewing-Machines, of which the following is a specification, reference being had therein to the accompanying drawings.

This invention relates to a chain-stitch sewing machine and particularly to mechanism for controlling the needle-thread thereof.

15 In the manufacture of gloves it is customary to stitch ornamental seams convergently disposed fanwise on the back thereof to impart to the article when finished a smart appearance which catches the pur- 20 chaser's eye. A variety of seams have previously been employed for this purpose but they have required more or less special stitch-forming mechanism. It is an object of the present invention to form an ornamental appear- 25 ing seam with a standardized type of stitch-forming mechanism whose thread control permits of concatenating the thread in a uniform manner and drawing the thread up with enough tension to enchain the loops 30 snug but not tight and without wrinkling the material between successive needle-punctures therein.

The invention consists essentially of nipping and pulling devices which are mounted 35 on the overhanging arm and actuated from the main-shaft below the work-support in such relative sequence that the pulling device acts to draw up a slight amount of slack thread between the needle and the supply before the nipping device grips the thread, after which the pulling device draws from the supply enough thread, but no more, than is required in the next stitch to be formed. It is preferably applied to a four-needle 45 four-looper type of single-thread chain-stitch machine making four independent seams in close and parallel rows and the thread may be of a color contrasting harmoniously with the material of the glove. 50 The invention in one of its forms is illustrated in the accompanying drawings in which Figure 1 is a rear elevation of a machine equipped therewith. Fig. 2 is a front elevation of the needle-bar, a portion of the 55 throat-plate and loopers appearing. Fig. 3

is an end elevation partly in section of the mechanism actuating the nipping and pulling devices. Fig. 4 is a plan view of the same. Fig. 5 is a perspective view on an enlarged scale showing the character of the 60 stitch formed and Fig. 6 is a perspective view of the nipping and pulling devices on top of the overhanging arm.

The machine illustrated is of the single-thread chain-stitch type employing four 65 needles 1 secured in a needle-clamp 2 of any suitable construction, the one shown being of the same construction as that disclosed in my copending application Serial No. 234,007 filed May 11, 1918, and also employing four 70 loopers 3 operated in any suitable manner from the main-shaft 4 which is located beneath the work-support 5 through slots in which feed-dogs 6 advance the work in a manner well known.

75 The needle-clamp 2 is secured to the lower end of a needle-bar 7 reciprocated by a link 8 connected to one end of a needle-lever 9 fulcrumed at 10 to the overhanging arm 11 and joined by a ball-and-socket connection 12 to a pitman 13 which is actuated from an eccentric 14 on the main-shaft 4.

The foregoing construction is old and well known to those skilled in the art. What is now to be described pertains particularly to 85 the new and novel thread control of the present invention.

Mounted on the needle-bar 7 is a plural-apertured thread-guide 15 of angular form which is adjustably secured by the screw- 90 and-slot connection 16 within a groove 17 formed in the collar 18 fast on the needle-bar.

95 Mounted on top of the overhanging arm 11 between the needle-bar and constant ten- sions 19, which may be of any suitable form and are of a number preferably correspond- ing to the number of needles, is a nipper which consists of a sheet-metal base 21 sup- porting at one end a spring 22 whose oppo- 100 site end is free to move up and down in proximity to a plurality of eyes 23 formed in the upright lip 24 at the end of the sheet-metal base. Threaded into the sheet-metal base 21 and passing loosely through the 105 spring 22 is a screw 25, which a clamp-nut 26 serves to hold in an adjusted position, the head of the screw 25 limiting the upward movement or flexure of the spring 22. The sheet-metal base 21 may be secured to the 110

overhanging arm by the screw 27, Figs. 3 and 6, or in any other suitable manner. The 5 spring 22 preferably has a wing 27' formed at the front edge thereof to prevent accidental displacement of the needle-threads which are adapted to pass over the spring as indicated by the dot-and-dash lines in Fig. 1. An arm or finger 28 extending at substantially right angles from the rod 29, as best 10 shown in Fig. 3, is moved during the operation of the machine into engagement with the spring 22 as will presently appear, the spring being free to grip all the threads against the finger.

15 Mounted also on top of the overhanging arm between the constant tensions 19 and nipper is a thread-puller which consists of fixed thread-restraining members or guides 31-32 of angular form in spaced relation 20 on opposite sides of a movable thread-engaging arm or finger 33 extending at substantially right angles from a rod 34, similar to the nipper finger and rod 28-29. One of the fixed thread-restraining devices, 31, is 25 provided with a U-shaped incision as shown and the other, 32, with a plurality of apertures 35'. Both of the fixed thread-restraining devices are secured to the overhanging arm by screws 35.

30 The rods 29 and 34 are passed through apertures 37-38, respectively, adjacent the nipper and thread-puller which are on top of the overhanging arm and at their lower ends these rods are suitably pivoted to 35 crank-arms 39-40 on a rock-shaft 41 which is parallel to the main-shaft 4 and is actuated from an eccentric 42 thereon embraced by a strap 43 that slidably receives a pin 44 fastened by the set-screw 45 to one end of 40 the rock-shaft.

The crank-arms 39-40 are so disposed and proportioned as to impart movements of different lengths and velocity to the bent ends or fingers 28-33 of the rods 29-34, 45 respectively. The resulting differential movement of the fingers 28-33 enables the nipper to grip the thread from about the time the looper sheds the previous needle-loop on the descent of the needle until after 50 the needle-eye in its succeeding ascent reaches the upper surface of the work. This timing of the contact and engagement of finger or thread-puller 28 with the spring 22, and of course the consequent grip of the 55 needle-threads passing between them, enables the thread-puller or finger 33 to perform a dual function during its down stroke. It first takes up some of the slack in the needle-thread while the needle descends to 60 loop-entering position and then, after the thread is gripped, it draws off from the supply through the constant tensions 19 that amount of thread which is required to form the next stitch.

65 In consequence of the action on the thread

above mentioned, an ornamental appearing seam may be formed with simple and inexpensive means applicable to a standardized type of machines without limiting or reducing the speed at which the machine may be 70 run. The thread control insures a degree of snugness to the loops of the finished parallel seams that enables them to spread and cover a glove back or other article without however being loose enough to catch and 75 open in the every-day use to which the same is subjected.

Having thus set forth the nature of the invention, what I claim herein is—

1. In a chain-stitch sewing machine stitch-forming mechanism including a needle-bar and a needle carried thereby, a work-feeding mechanism in combination with needle-thread controlling mechanism comprising an eye carried by the needle-bar adjacent its 80 upper end, a constant tension between the needles and the supply, an intermittent tension between the eye carried by the needle-bar and the constant tension, and a combined take-up and pull-off means between 85 the intermittent and constant tensions said intermittent tension being adapted to grip the thread about the time the looper sheds its loop and to maintain its hold on the thread until the eye of the needle reaches 90 the work in its ascent, and said combined take-up and pull-off means being adapted to first draw thread from the portion thereof leading to the needle and subsequently to 95 draw thread from the supply. 100

2. In a chain-stitch sewing machine in combination, stitch-forming mechanism including a needle and a looper in combination with needle-thread controlling mechanism including intermittent and constant tensions and an intermediate thread-puller, said intermittent tension being actuated to 105 grip the thread between the beginning and ending of the movement of the thread-puller whereby the latter functions first as a take-up and then as a pull-off on the descent of 110 the needle. 115

3. In a single thread chain-stitch sewing machine, in combination, stitch-forming mechanism including a needle, work-feeding mechanism, means for controlling the thread including intermittent and constant tensions and also including a thread-puller located between said tensions, and means for relatively actuating said intermittent tension 120 and said pull-off causing the latter to first draw upon the slack-thread between needle and the nipper during the descent of the needle and to draw subsequently from the supply through the constant tension and during the descent of the needle the amount of thread required to form a stitch whereby successively enchain loops of needle-thread may open sufficiently to present an ornamental appearance and free the mate- 125 130

rial between the successive needle punctures of strain without leaving the successively enchain loops free to stand away from the work.

- 5 4. In a single-thread chain-stitch machine, in combination, stitch-forming mechanism including an eye-pointed needle, work-feeding mechanism, and thread controlling mechanism including a take-up eye fixed to the 10 needle-bar, a nipper, a thread-puller, means for actuating said nipper and thread-puller to draw slack from the needle until it enters a loop of needle-thread on the looper and to draw thread from the supply which latter is 15 not available until after the eye of the needle reaches the work in its ascent.

- 5 5. In a single-thread chain-stitch sewing machine, in combination, stitch-forming mechanism including an eye-pointed needle, 20 work feeding mechanism, an eye carried by the needle-bar, a nipper, a thread-puller on the supply side of the nipper, a constant tension on the supply side of the thread-puller, said nipper being actuated to grip 25 the thread between the beginning and ending of the drawing action of the thread-puller to allow the latter to draw up some of the slack thread between the needle and nipper during a portion of the descent of the 30 needle and to draw thread from the supply during the remainder of the needle's descent.

- 6 6. In a single-thread chain-stitch sewing machine, in combination, stitch-forming mechanism including a needle, work-feeding 35 mechanism, a take-up eye on the needle-bar, a nipper, a thread-puller on the supply side of the nipper, a constant tension on the supply side of the thread-puller means for actuating the thread-puller to draw some of the 40 slack thread between the needle and nipper during the descent of the needle and until it has entered the needle-loop on the looper, means for actuating the nipper to grip the thread when the needle has entered the needle-loop on the looper, and for maintaining the nipper's grip on the thread until the eye of the needle is above the work in its ascent.

- 7 7. In a sewing machine having an overhanging arm and stitch-forming mechanism 50 including a needle, a main-shaft, a rock-shaft driven therefrom, a nipper, a thread-puller, connections between the rock-shaft and both the nipper and thread-puller, said connections being constructed and arranged 55 to time the nipper's grip between the beginning and ending of the descent of the thread-puller.

- 8 8. In a single-thread chain-stitch machine, in combination, an overhanging arm, stitch-forming mechanism including a needle, a 60

nipper for gripping the needle-thread, a thread-puller having fixed and movable members, a main-shaft, a rocking member driven therefrom, and connections between the movable member of the thread-puller 65 and the nipper for gripping the needle-thread between the beginning and ending of the drawing action of the pull-off to cause the latter to first take thread from the needle's side thereof and to subsequently take 70 thread from the supply side thereof, said means holding the needle-thread gripped by the nipper until the eye of the needle reaches the work in its ascent.

9. In a sewing machine having stitch-forming mechanism including a needle, a main-shaft, a rock-shaft driven therefrom, a plurality of arms on said rock-shaft, reciprocatory members connected to said plurality of arms, a nipper interposed in the path 80 of one of said reciprocatory members, thread confining means located adjacent the other of said reciprocatory members, and means confining the reciprocatory members to movement in a prescribed path. 85

10. In a sewing machine having stitch-forming mechanism including a needle, a cloth-plate, an arm overhanging the cloth-plate, a main shaft located below the cloth-plate, a rock-shaft, a pair of arms of different lengths on said rock-shaft, a nipper supported by the overhanging arm, thread restraining means on the overhanging arm between the nipper and the supply, fingers adjacent the nipper and thread restraining 95 means, said fingers being confined adjacent said overhanging arm and being also connected to the arms of the rock-shaft. 90

11. In a sewing machine having stitch-forming mechanism and work-feeding mechanism, in combination, a cloth-plate, an arm overhanging the cloth-plate, a main-shaft located below the cloth-plate, a rock-shaft, an eccentric on the main-shaft, a strap embracing said eccentric and having a pin and 100 socket connection with the rock-shaft whereby the rock-shaft is oscillated, a plurality of arms of different lengths on said rock-shaft, a nipper, a constant tension device on said overhanging arm, spaced thread guides intermediate said nipper and constant tension, and means moving between said spaced thread-guides and also down upon said nipper for pulling off and gripping respectively the needle-thread, said means being connected to said arms on the rock-shaft. 110 115

In testimony whereof, I have signed my name to this specification.

ALBERT H. DE VOE.
